United States Patent Office

Des. 220,049
Patented Mar. 2, 1971

220,049

MODEL RACING CAR

Bruce Leslie McLaren, Weybridge, England, assignor to
Bruce McLaren Motor Racing Limited, Colnbrook,
Buckinghamshire, England

Filed Jan. 14, 1970, Ser. No. 20,922

Claims priority, application Great Britain July 26, 1969

Term of patent 7 years

Int. Cl. D21—02

U.S. Cl. D34—15

FIG. 1 is a top plan view of the model racing car,
 FIG. 2 is a front elevation,
 FIG. 3 is a side elevation,
 FIG. 4 is a rear elevation.

The opposite side of FIG. 3 is identical to the side shown.

I claim:

The ornamental design for a model racing car, as shown.
